7 Claims. (Cl. 12—55)

This invention relates to apparatus used primarily in the shoe industry for folding the edges of a cut-out, as where the vamp of a lady's shoe is provided with a relatively small cut-out in the area of the throat. Where such cut-outs are provided, the margins of the work piece surrounding the cut-outs are doubled back to form a finished edge, a suitable bonding adhesive or cement being first applied to the areas to be doubled back or the areas against which the doubled back portions to be juxtaposed so that the parts will be secured together in the folded condition. Often a stiffening element, such as stiff paper or similar material, is cemented to the work piece before the margins are folded the positioning of the stiffener being such that the marginal areas will be folding about the edges of the stiffener and will be cemented to the exposed surface thereof.

The instant invention relates to apparatus particularly designed to fold the inside edge portions of a cut-out formed in a work piece, such as a shoe vamp, the marginal edge portions being folded and secured by the co-action of upper and lower die members during a single stroke press operation.

A principal object of the instant invention is the provision of edge folding apparatus comprising coacting upper and lower die assemblies, the lower die assembly having a spring biased die member displaceable vertically upon contact therewith by the die member of the upper die assembly which is operatively connected to the plunger of a conventional bench type cut-out machine of the character employed in the shoe manufacturing plant to perform a variety of cutting operations.

A further object of the instant invention is the provision of apparatus of the character described wherein a masking plate overlies the lower die assembly, the masking plate being hinged to the lower die assembly for movement from an open to a closed position, the masking plate additionally incorporating a sliding gauge plate which, when in operative position, serves to initially fit the cut-out in the work piece about the lower die element, whereupon the gauge plate is moved to its inoperative position prior to the press operation.

Still a further object of the invention is the provision of apparatus of the character described which is of simplified construction and easily manipulated by the operator, the sliding gauge plate serving to enable the operator to easily and quickly position the work piece relative to the lower die member, while at the same time assuring proper alignment and positioning of the marginal edge portions which are to be folded. The foregoing together with other objects to the invention which will appear hereinafter or which will be apparent to the skilled worker in the art upon reading this specification, are accomplished by that construction and arrangement of parts of which an exemplary embodiment shall now be described.

Reference is made to the accompanying drawings wherein:

FIGURE 1 is a plan view of a shoe vamp having a cut-out the edges of which are to be folded.

FIGURE 2 is an enlarged fragmentary plan view of the lower die member, with the initial position of the work piece illustrated in dotted lines.

FIGURE 3 is an enlarged fragmentary side elevational view of the lower die showing the work piece as initially positioned relative to the gauging head.

2

FIGURE 4 is an enlarged fragmentary side elevational view of the upper die member.

FIGURE 5 is a bottom plan view of the upper die member.

FIGURE 6 is a fragmentary side elevational view of the dies illustrating the manner in which the gauge plate presses the work piece downwardly about the body of the lower die member with the marginal edge portions deflect upwardly into contact with the wall surfaces of the lower die member.

FIGURE 7 is a side elevational view with parts in section illustrating the masking plate and sliding gauge plate as the latter contacts the work piece.

FIGURE 8 is a plan view of the lower die assembly with the sliding gauge plate shown in the retracted or inoperative position.

FIGURE 9 is a partial plan view similar to FIGURE 8 but illustrating the sliding gauge plate and its extended or operative position.

FIGURE 10 is an elevational view similar to FIGURE 6 but illustrates the positioning of the parts at the commencement of the press operation.

FIGURE 11 is also an elevational view similar to FIGURE 6 but illustrates the position of the parts at the bottom of the stroke of the upper die member.

Briefly, in the practice of the invention upper and lower die assemblies are provided, the upper die assembly comprising a mounting plate adapted to be secured to the plunger of a conventional bench type cut-out machine having a fixed base and an overlying reciprocating plunger which, upon actuation, moves the upper die assembly downwardly into contact with the lower die assembly and the work piece, whereupon the upper die assembly is returned to its starting position. The lower die assembly comprises a base plate which supports a subplate spaced upwardly from the base plate, the subplate serving as a mounting means for the hinged mask plate and the sliding gauge plate mounted thereon. The lower die member projects upwardly through an opening in the subplate, the lower die member being mounted on a vertically movable supporting plate having spring means which normally bias the lower die member to an upper position in which it projects upwardly through the opening in the subplate.

The lower die member is provided at its uppermost end with a gauging head of the size to fit within the initial cut-out opening in the work piece, the lower die member having an enlarged shoulder surrounding the gauging head which corresponds in size to the final size of the cut-out opening being formed. The upper die member has a recess in its under-surface of the size to receive the gauging head when the dies are brought together, the recess being surrounded by a ledge adapted to seat on the enlarged shoulder of the lower die member. A vertical wall surface projects upwardly from the outermost extremity of the ledge and terminates in an outwardly flared shoulder which, when the die members are reciprocated, coacts with the subplate of the lower die assembly to fold the marginal edge portions surrounding the cut-out opening back onto the work piece.

The cut-out in the work piece is adapted to be seated on the gauging head of the lower most die, whereupon the hinged masking plate is lowered with the sliding gauge plate in its forward or operative position. The gauge plate has an opening therein of the size to surround the lower die member so that, as the plate is brought downwardly over the work piece, it forces the work piece downwardly around the lower die member and in so doing the marginal edge portions to be folded are caused to be bent upwardly so that they lie along the vertical wall surfaces of the lower die member. When the work piece has been seated

on the subplate of the lower die assembly, the gauge plate is retracted, the work piece being firmly held against the subplate by the underlying masking plate which has a somewhat larger opening therein surrounding the lower die member. Upon actuation of the plunger carrying the upper die assembly, the die assembly moves downwardly and the upper die member acts to move the lower die member downwardly through the opening in the subplate. As the die members move downwardly the upwardly projecting marginal portions of the work piece come into contact with the flared shoulder of the upper die which folds them outwardly and juxtaposes the marginal edge portions against the underlying portions of the work piece, which is supported from beneath on the subplate. Suitable adhesive and/or a stiffener will have been previously applied to the work piece in the area surrounding the marginal portions to be folded, and under the pressure of the upper die the marginal portions will be pressed into tight contact with the underlying areas of the work piece. Upon subsequent upward movement of the upper die assembly, the operator then lifts the masking plate and removes the work piece.

For a detailed description of the invention, reference is now made to FIGURE 1 of the drawing which illustrates a shoe upper or vamp 1 for a ladies shoe, the vamp being provided across the throat with a cut-out 2 the edges of which are defined by lines of cut demarking marginal edge portions 3 which are to be infolded and adhered to the inner surface of the piece. It is to be understood at the outset that the work piece illustrated is exemplary only and that the invention will find utility in conjunction with the formation of a finished edge cut-out in any type or style of work piece.

The lower die member 4, which is seen in FIGURES 2 and 3, has a gauging head 5 at its uppermost end of the size to conform to the cut-out 2 in its initial condition, i.e., the size of the cut-out prior to the folding of the marginal portions 3. An outwardly projecting enlarged shoulder 6 surrounds the gauging head 5, the outermost edge 7 of the enlarged shoulder defining the ultimate outline of the cut-out being formed, i.e., it corresponds to the base edges of the marginal portions 3. The lower die member has a vertical wall surface 8 which also corresponds to the ultimate size of the cut-out being formed. The lower die member is vertically reciprocable relative to the subplate 9 which, as will be explained in greater detail hereinafter, forms a part of the lower die assembly, the die member 4 projecting upwardly through an opening 10 in the subplate. FIGURE 2 also serves to illustrate the manner in which the work piece, shown in dotted lines, is initially associated with the lower die member, the operator fitting the cut-out 2 around the gauging head 5 with the marginal edge portions 3 seated on the enlarged shoulder 6.

The upper die member 11 is seen in FIGURES 4 and 5. On its under surface it has a ledge 12 of a size to mate with the enlarged shoulder 6 of the lower die member, the ledge surrounding a recess 13 which is dimensioned to receive the gauging head 5 of the lower die when the two dies are brought together. A vertical wall surface 14 projects upwardly from the outermost edge of the ledge 12, the wall surface 14 defining a continuation of the vertical wall surface 8 of the lower die member when the two members are brought together. The wall surface 14 terminates upwardly in an outwardly flared shoulder 15 which defines the under surface of the die body 16.

Referring now to FIGURE 7, the upper die member 11 is secured to a mounting plate 17 having an attachment plug 18 by means of which the assembly may be secured to the reciprocating plunger of a cut-out machine. The lower die member 4 is mounted on a movable plate 19 underlying subplate 9, the plate 19 being normally urged upwardly by means of springs 20 and surrounding guide pins 21 which projects downwardly through openings 22 in the base plate 23 and mounting block 24 which, as

will be understood, is fixedly secured to the cut-out machine. The subplate 9 is mounted in spaced relation to the base plate 23 by means of legs 25 and hence is stationary with respect thereto.

With reference to both FIGURES 9 and 10, the subplate 9 mounts a masking plate 26 which is hingedly connected thereto by means of hinges 27. Wherein the closed position, the masking plate 26 overlies the subplate 9 and has an opening 28 therein of size to freely surround the lower die member 4, the opening 28 being spaced outwardly from the lower die member by a distance greater than the outermost extent of the body 16 of the upper die member so that the outwardly flared shoulder 15 of the upper die may seat against the subplate 9 during the pressing operation.

The masking plate 26 is provided along its opposite side edges with a pair of guides 29 and 29a which slidably mount a gauge plate 30 slidable in the guide from a rearward or inoperative position, as illustrated in FIGURE 8, to a forward or operative position, as illustrated in FIGURE 9. The gauge plate 30 is adapted to be moved from one position to the other by means of the forwardly projecting arm 31 which may also be used by the operator to raise and lower the masking plate 26. The gauge plate 30 has an opening 32 of a size to surround in close conformity to the vertical wall surface 8 of the lower die member 4 when the gauge is in its forward or operative position.

In using the apparatus, the operator first raises the masking plate 26, which can be readily done since the upper die assembly will be elevated excepting during the pressing operation. A work piece is placed over the lower die member with the cut-out surrounding the gauging head 5 of the lower die member in the manner previously de-

scribed in conjunction with FIGURE 2 of the drawings. While the masking plate is elevated—usually as an incident of raising it—the gauge plate 30 is moved to its forward or operative position so that, once the work piece has been initially positioned on the lower die member,

downward movement of the masking plate will cause the plate to contact the work piece and force it downwardly. As this takes place, the edges of opening 32 in gauge plate 30 will contact the work piece along the base ends of the cut-out portions 3, as will be evident from FIGURE 9, and as the downward movement continues the gauge plate

will force the work piece downwardly about the outermost edge of the enlarged shoulder 6, thereby bending the marginal edge portions 3 upwardly as they slide along the vertical wall surface 8 of the lower die member. This action can be seen in FIGURE 6 which illustrates the action which takes place as the masking plate and gauge plate pass downwardly along the lower die member.

When the masking plate has been seated against the subplate 9, the parts assume the condition illustrated in FIGURE 10, whereupon the operator moves the gauge plate 30 rearwardly to its inoperative position, so that portions of the underlying work piece surrounding the lower die member are exposed through the larger opening 28 in the masking plate 26. The operator then actuates the plunger mounting the upper die assembly, whereupon the upper

die member 11 moves downwardly into contact with the lower die member 4 and, as the downward movement continues, the upper die member depresses the lower die member. As the upper die member approaches the upturned marginal edge portions 3 of the work piece, the edge portions slide along the vertical wall surface 14 of the upper die member and are folded outwardly as they are contacted by the outwardly flared shoulder 15. The marginal edge portions are thus reversely bent with respect to the underlying work piece and are flattened thereagainst by

the shoulder 15 as the parts assume the position as illustrated in FIGURE 11. The upper die assembly then retracts and the parts return to their initial position. The operator then lifts the masking plate and removes the work piece by lifting it upwardly from the lower die member.

Modifications may be made without parting from the spirit and purpose of the invention, and it is to be understood that the invention is not intended to be limited excepting in the manner set forth in the claims which follow.

The embodiments of the invention in which an exclusive property or privilege is claimed are defined as follows:

1. In apparatus for forming a finished edge cut-out in a work piece, an upper die assembly mounting an upper die member, and a lower die assembly mounting a lower die member having a gauging head for initially positioning a work piece relative to said lower die, said lower die having an enlarged shoulder surrounding the gauging head, the outermost edge of said enlarged shoulder defining the outline of the finished cut-out, a vertical wall surface extending downwardly from the outermost edge of said enlarged shoulder, which vertical wall surface also defines the outline of the finished cut-out, said lower die assembly including a subplate having an opening therein of a size to receive said lower die member, means mounting said lower die member for vertical movement relative to the opening in said subplate, said mounting means including resilient means normally biasing said lower die member upwardly so that it projects through the opening in said subplate, the undersurface of said upper die defining a ledge of a size to mate with the enlarged shoulder of the lower die member when the die members are brought together, a recess in said ledge of a size to receive said gauging head, said upper die having a vertical wall surface projecting upwardly from the outermost edge of said ledge, said last named wall surface also corresponding to the outline of the finished cut-out, the vertical wall surface of the upper die terminating upwardly in an outwardly flared shoulder adapted, when the dies are displaced downwardly, to seat against said subplate in an area surrounding the opening therein.

2. The apparatus claimed in claim 1 including means operatively connected to said lower die assembly for contacting a work piece fitted over the gauging head of the lower die member with the marginal portions thereof to be folded seated on said enlarged shoulder and forcing the work piece downwardly along the vertical wall surfaces of said lower die member, thereby causing the said marginal portions of the work piece to be folded upwardly.

3. The apparatus claimed in claim 2 wherein said last named means comprises a masking plate hingedly connected to said subplate, said masking plate mounting a slideable gauge plate having an opening therein of a size to contact the work piece along the base edges of the said marginal edge portions thereof, said gauge plate being movable from an operative to an inoperative position.

4. The apparatus claimed in claim 3 wherein said masking plate has an opening therein which surrounds said lower die member but is spaced outwardly therefrom by a distance greater than the cross-sectional dimensions of the outwardly flared shoulder of said upper die member, whereby the shoulder of said upper die member may seat against said subplate when said masking plate is juxtaposed thereto.

5. In apparatus for forming a finished edge cut-out in a work piece, an upper die assembly mounting an upper die member, and a lower die assembly mounting a lower die member having a gauging head for initially positioning the work piece relative to said lower die, said lower die having an enlarged shoulder surrounding the gauging head, the outermost edge of said enlarged shoulder defining the outline of the finished cut-out, a vertical wall surface extending downwardly from the outermost edge of said enlarged shoulder, which vertical wall surface also defines the outline of the finished cut-out, said lower die

assembly including a subplate having an opening therein of a size to receive said lower die member, a vertically movable mounting plate underlying said subplate mounting said lower die member for vertical movement relative to the opening in said subplate, spring means normally biasing said mounting plate upwardly so that said lower die member projects upwardly through the opening in said subplate, the undersurface of said upper die defining a ledge of a size to mate with the enlarged shoulder of the lower die member when the die members are brought together, a recess in said ledge of a size to receive said gauging head, said upper die having a vertical wall surface projecting upwardly from the outermost edge thereof, said last named wall surface also corresponding to the outline of the finished cut-out, the vertical wall surface of said upper die member terminating upwardly in an outwardly flared shoulder adapted, when the dies are displaced downwardly, to seat against said subplate in an area surrounding the opening therein, and a masking plate hingedly connected to said subplate and movable from an operative position in which said masking plate overlies said subplate to an inoperative position in which it is elevated with respect to the subplate and said lower die member so that a work piece may be fitted over the gauging head of the lower die member, said masking plate including means operative to contact a work piece fitted over the gauging head of said lower die member and force said work piece downwardly about said lower die member.

6. The apparatus claimed in claim 5 wherein said last named means comprises a sliding plate mounted on said masking plate and movable from a retracted to an extended position, and an opening in said sliding plate of a size to surround the vertical wall surface of said lower die member when said sliding plate is in its extended position.

7. In apparatus for forming a finished edge cut-out in a work piece, wherein an upper die assembly mounting an upper die member is adapted to be juxtaposed to a lower die assembly mounting a lower die member having a gauging head for initially positioning the cut-out in a work piece relative to said lower die member, said lower die member projecting upwardly through an opening in a subplate and being movable downwardly therethrough when contacted by the upper die member, the improvement which comprises a masking plate assembly for initially fitting the work piece over said lower die member, said assembly comprising a masking plate hingedly connected to said subplate and movable from an operative position in which said masking plate is juxtaposed to said subplate to an inoperative position in which said masking plate is elevated relative to said subplate and said lower die member so that the cut-out in the work piece may be fitted over the gauging head of said lower die member, a sliding gauge plate mounted on said masking plate, said sliding gauge plate being movable from a retracted to an extended position, an opening in said sliding plate positioned to surround said lower die member when said plate is in its extended position, whereby the work piece will be contacted by said gauge plate and forced downwardly over said lower die member as said masking plate is moved from the inoperative to the operative position, whereupon said sliding plate may be retracted to expose underlying portions of the work piece.
